United States Patent Office

Des. 203,324
Patented Dec. 21, 1965

203,324

FAUCET FIXTURE

Harper Landell, Whitemarsh, Pa., assignor to Speakman Company

Filed Dec. 8, 1964, Ser. No. 82,958

Term of patent 14 years

(Cl. D91—3)

FIG. 1.

FIG. 3.

FIG. 2.

FIG. 4.

FIG. 5.

I claim:

The ornamental design for a faucet fixture, as shown and described.
